UNITED STATES PATENT OFFICE.

WILLIAM U. DENNISON, OF YOUNGSTOWN, OHIO.

SLIP PINION.

Application filed April 6, 1922. Serial No. 550,909.

To all whom it may concern:

Be it known that I, WILLIAM U. DENNISON, a citizen of the United States, and resident of Youngstown, in the county of Mahoning and State of Ohio, have invented certain new and useful Improvements in Slip Pinions, of which the following is a specification.

This invention relates to slip pinions and while not limited thereto relates more particularly to slip pinions adapted for use on the pinion shaft of rolling mills and has for its object the provision of a slip pinion construction that will permit the shaft on which the pinion is mounted to rotate freely at a greater speed than the pinion and will grip the shaft when the shaft tends to rotate at a lesser speed than the pinion.

Another object is to provide a slip pinion having the novel design, construction and combination of parts illustrated in the accompanying drawings and described in the following specification.

It is well known that in certain rolling mill operations a better product is obtained when the top roll of a mill is allowed to drift along. Heretofore this drifting has been accomplished by removing the driving spindle, which connects the top roll with its driving pinion shaft, thus permitting the top roll to rest on the bottom roll or on the metal between the rolls and to drift along with the bottom roll. However, under this old practice when metal enters the rolls it forces the top roll against the adjusting screws, producing a shock or blow which damages the adjusting screws, gears, bearings and other parts.

The ideal drifting can be accomplished by the present invention while at the same time the top roll may be kept in its highest position and thereby eliminate the shock produced by metal entering the rolls under the old practice.

It will be understood, however, that while I have selected a pinion shaft and pinion of a rolling mill to illustrate my invention it is not limited to such use, but may be applied to any driving and driven member where it is desired to get the result obtained by this invention.

In the drawings, Figure 1 is a side elevation of a shaft having two pinions thereon and embodying this invention.

Figure 2 is a longitudinal sectional view of the shaft and pinions of Figure 1.

Figure 3 is a cross sectional elevation on the line III—III of Figure 1.

Figure 4 is a detail elevation of one of the expandable sleeves.

Referring more particularly to the drawings, the numeral 2 designates the shaft as a whole, which is provided with an integral shoulder 3 having a flange 3^a. The shaft 2 is also provided with a portion 4 of reduced cross section which extends from the shoulder 3 to its one end.

A pair of pinions 5 and 6 are loosely mounted on the portion 4 of the shaft, and expandable sleeve members 7 and 8 are mounted on the shaft within the pinions 5 and 6 respectively. The sleeves 7 and 8 are provided with a spiral or helical slot 9 so as to form a sleeve that is resilient and resembles a coil spring. One end of each of the sleeves 7 and 8 is provided with an inwardly extending lug 10 which is secured or engaged in a slot in the shaft 2 and locks the one end of the sleeves against movement. The sleeves 7 and 8 are mounted on the shaft 2 under tension, so that they will grip the internal surface of the pinions and frictionally hold said pinions on the shaft.

The pinion 5 fits over the flange 3^a and abuts the shoulder 3. A loose collar 11 is mounted on the shaft 2 between the pinions 5 and 6 and is provided with reduced flanges 12 and 13 adapted to fit within the pinions 5 and 6. The collar 11 serves to hold the sleeves 7 and 8 and pinions 5 and 6 in spaced relation.

An elongated sleeve 14 having an end flange 15 adapted to abut the end of the shaft 2 and provided with a shoulder 16 and flange 17 on its other end is mounted on the reduced portion 4 of the shaft with the flange 17 extending within the pinion 6, and the shoulder 16 abutting the end of said pinion. The shaft 2 is provided with a screw threaded extension 18 which extends beyond the end flange 15 of the sleeve 14 and has nuts 20 threaded thereon and engaged against the flange 15 of the sleeve 14 to lock the assembly in place.

The operation of the apparatus above described is as follows—

Assuming that the apparatus is assembled and power is being applied to the pinions 5 and 6 to rotate the shaft in a counter-clockwise direction, when looping at the threaded extension 18, if the shaft 2 lags or tends to turn at a slower speed than the pinions, the

sleeves 7 and 8 will expand, due to the friction between the sleeves and the pinions 5 and 6, and the fact that the sleeves are locked by the lugs 10 at one end on the shaft 2, thus 5 they gradually increase in size and more tightly grip the pinions. In case the opposite action is had, that is, in case the shaft 2 tends to rotate at a greater speed than the pinions 5 and 6, the effect on the sleeves 7 and 10 8 will be the reverse to that described above. That is, the sleeves 7 and 8 will be compelled to contract and release their hold on the pinions 5 and 6, thereby allowing said shaft to rotate freely. This action would be substantially the same as if the pinions 5 and 6 15 were held stationary while the shaft was rotated in a counter-clockwise direction when looking at the threaded extension 18.

In driving rolls of a rolling mill it has 20 been the practice to use two-faced pinions. That is, pinions having one series of teeth extending over approximately one-half of the width of the pinion and a second series of teeth extending over approximately the 25 other half thereof, the one series of teeth being in staggered relation with the teeth of the other series. That is, the one series of teeth being opposite the spaces between the teeth of the other series. This arrangement 30 of pinion teeth provides a construction in which there is always more than one tooth in mesh, and thus provides greater strength and prevents backlash. In view of this practice I have shown my invention as applied 35 to two pinion segments adapted to mesh with the old form of two-faced pinion, although it will be understood that I do not wish to be limited to this construction, since my invention may readily be applied to a single- 40 faced or single pinion.

While I have shown and described one specific embodiment of my invention, it will be understood that various modifications in design, construction, and combination of parts may be made without departing from 45 the scope of my invention as defined in the appended claims.

I claim—

1. The combination with a shaft having a shoulder formed integral thereon, of a pair 50 of pinions mounted loosely on said shaft, an expansible sleeve mounted between each of said pinions and said shaft, said sleeves being secured to said shaft and frictionally engaging said pinions, a collar mounted between said pinions to hold them in spaced relation, one of said pinions being mounted on said shaft so as to abut said shoulder, an elongated sleeve member fitted on said shaft and provided with a shoulder adapted to 55 abut the other of said pinions, and means for locking said sleeve in position on said shaft.

2. The combination with a shaft having a shoulder formed integrally thereon, of at 60 least one pinion mounted loosely thereon, said pinion having one end abutting said shoulder, an annular expansible sleeve mounted between said pinion and said shaft, said sleeve having one end secured to said shaft and having direct frictional engagement only with said pinion, and means abutting the other end of said pinion, including a sleeve fitted on said shaft, said sleeve being 65 locked in position by nuts screwed on a reduced extension of said shaft and engaging the end of said sleeve.

In testimony whereof I have hereunto set my hand.

WILLIAM U. DENNISON.
